UNITED STATES PATENT OFFICE.

KAUFMAN HOLTZ, OF ROCHESTER, NEW YORK.

TAG.

1,262,343.

Specification of Letters Patent.

Patented Apr. 9, 1918.

Application filed July 14, 1917. Serial No. 180,676.

To all whom it may concern:

Be it known that I, KAUFMAN HOLTZ, a citizen of the United States, residing at Rochester, in the county of Monroe and State 5 of New York, have invented certain new and useful Improvements in Tags, of which the following is a specification.

The object of this invention is to provide the tags or tickets used to identify or 10 scribe cloth or any other flexible fabric with new and improved fasteners with which these tags or tickets are readily attached to the fabric and rigidly held in place thereon.

This and other objects of this invention 15 will be fully illustrated in the drawing, described in the specification and pointed out in the claim at the end thereof.

In the accompanying drawing,

Figure 1 is a perspective view of a label 20 provided with the fasteners.

Fig. 2 is an enlarged perspective view of one of the fasteners.

Fig. 3 is a cross section through a piece 25 of cloth with one of the labels attached thereto.

In the several figures of the drawing like reference numerals indicate like parts.

As shown in the figures each of the fasteners is bent up of a single piece of wire into 30 the form of a staple which is provided with pin points 1 and 2 on one side and the loop 3 on the other side.

These staples are inserted into the tag 4, preferably one near each corner thereof, and 35 in such a manner that the loop 3 of each of the staples can be bent over the edge of the tag and folded over a portion of the back thereof.

Each of the staples is thus rigidly held in 40 place at suitable points on the tag 4, the shanks of the pin points 1 and 2 are then offset with a shoulder 5 which projects toward the back of the label for a purpose that will presently appear.

When it is desired to attach the tag 4 to a piece of fabric, one side thereof is hooked into the fabric until the pin points 1 and 2 of the staples project through the cloth and emerge on the other side thereof. The 45 shanks of the pin points 1 and 2, which have been previously bent to project with the back of the tag, as shown in Figs. 1 and 3, press snugly against the back of the fabric after the staples are hooked into it.

50 When in this position the offset or shoul-

der 5, provided on each of the shanks, projects into the fabric and acts as a retainer for each of the shanks which prevents them from sliding out of engagement with the fabric after they are engaged therewith.

When one end of the tag 4 is hooked into the fabric as above pointed out, the portion of the fabric to which the other end of the tag is to be attached is moved toward the portion of the fabric which is already attached to it. In doing this the length of the fabric bends out and away from the label into the position shown in dotted lines in Fig. 3. In this position the pin points of the staples on the free end of the label are 60 hooked into the fabric so that when the fabric is again straightened out the shanks of these pin points pass through the fabric and engage it in the same manner as did the shanks of the staples on the opposite end of 65 the tag.

The tag is thus snugly held in place on the fabric and cannot accidentally detach itself from it as the shoulder 5 prevents the shanks of the staples from sliding out of 70 engagement with the fabric and also for the reason that the fabric, when being straightened out after the second set of staples is hooked into it, is shortened, as the distance of the fabric between the points of engagement is shortened, which prevents the shanks from sliding one way or the other so that the label cannot come off after once being attached thereto.

I claim:

A tag comprising a ticket having a series of staples attached thereto, each of said staples comprising a single piece of wire, said wire being bent into the form of a loop on one side thereof and terminating into a pair of 95 pin points on the other side thereof, shanks connecting said pin points with said loop, said shanks passing through said ticket, the portions of said shanks projecting through the front of said ticket and terminating in 100 said loop being folded over the edge of said ticket and on to the back thereof, the portions of said shank projecting through the back of said ticket being bent parallel to said ticket and having a shoulder offset 105 therein, said shoulder projecting toward the back of said ticket.

In testimony whereof I affix my signature.

KAUFMAN HOLTZ.
